engages two adjacent floor boards or sleepers, the prong 18 engaging the tongue side of one board and the angular flange 17 engaging the groove of the next adjacent board so that both boards are firmly attached to the I-beam at this point.

In Figs. 4 and 5 is shown a form of the invention especially adapted for attaching tongue and groove roofing boards to structural channel purflins. In this case the roofing boards are of much lighter construction than the bridge flooring shown in Figs. 1 and 2 and the metal cleats or clips indicated generally at 15a may therefore be smaller and of lighter material.

15 Each of the cleats 15a is provided with a tapered recess 16a adapted to tightly fit upon the upper tapered flange 11a of one of the structural channel purlins 10a and is provided at its upper edge with the right angle flange 17a adapted to be received within the groove 13a of one of the roof-
20 ing boards 12a and has the sharpened prong 18a stamped from the body portion of the cleat just below the flange 17a and adapted to be driven into the tongue edge of the adjacent board just below the tongue thereof in the same manner as
25 shown in Fig. 1.

The cleat 15a is provided with an extension 20 extending beyond the channel purlin 10a and having the angular ear 21 adapted to be bent downward against the back surface of the purlin as shown in 21a in Fig. 4, thus locking the cleat against lateral movement across the purlin and holding each roofing board against longitudinal movement with reference to the purlin.

a sheet metal cleat having a tapered recess for tightly fitting upon the flange, an angular flange at the top of said cleat for engagement in the groove of one of the wooden members the width of said angular flange being less than the depth of said groove, and an integral sharp prong upon the cleat oppositely disposed to said angular flange for engaging below the tongue of the adjacent wooden member.

2. In combination with a structural metal member having a tapered flange, tongue and groove wooden members extending across the flange, and a sheet metal cleat having a tapered recess for tightly fitting upon the flange, an angular flange at the top of said cleat for engagement in the groove of one of the wooden members, an integral sharp prong upon the cleat for engaging below the tongue of the adjacent wooden member, and means upon the cleat for engaging the structural metal member at a point opposite to said tapered flange. 20

3. In combination with a structural metal member having a tapered flange, tongue and groove wooden members extending across the flange, and a sheet metal cleat having a tapered recess for tightly fitting upon the flange, an angular flange at the top of said cleat for engagement in the groove of one of the wooden members, an integral sharp prong upon the cleat for engaging below the tongue of the adjacent wooden member, an extension upon the metal cleat beyond the tapered recess therein, and an angular ear upon said extension adapted to be bent into engagement with the structural metal member at a point opposite to said tapered flange. 35
